US0D1046606S

(12) **United States Design Patent** (10) **Patent No.:** **US D1,046,606 S**
(45) **Date of Patent:** ** *Oct. 15, 2024

(54) **MAGNETIC HOOK APPARATUS**

(71) Applicant: **Encore Packaging LLC**, Lake Villa, IL (US)

(72) Inventor: **Timothy H. Nelson**, Winnetka, IL (US)

(73) Assignee: **Encore Packaging LLC**, Lake Villa, IL (US)

(*) Notice: This patent is subject to a terminal disclaimer.

Patent file contains an affidavit/declaration under 37 CFR 1.130(b).

(**) Term: **15 Years**

(21) Appl. No.: **29/837,259**

(22) Filed: **May 4, 2022**

Related U.S. Application Data

(63) Continuation of application No. 29/716,132, filed on Dec. 6, 2019, now Pat. No. Des. 954,544.

(57) **CLAIM**

The ornamental design for a magnetic hook apparatus as shown and described.

DESCRIPTION

FIG. 1 is a front-top perspective view of a magnetic hook apparatus showing my new design;

FIG. 2 is a bottom-rear perspective view thereof;

FIG. 3 is a right side elevation view thereof;

FIG. 4 is a left side elevation view thereof;

FIG. 5 is a rear elevation view thereof;

FIG. 6 is a front elevation view thereof;

FIG. 7 is a top view thereof; and,

FIG. 8 is a bottom view thereof.

The drawings contain symbolic breaks. The portions between the break lines form no part of the claimed design. The dash-dash broken lines are included for the purpose of illustrating environmental structures and form no part of the claimed design.

1 Claim, 6 Drawing Sheets
